UNITED STATES PATENT OFFICE.

GEORGE L. GOODRICH, OF BRISTOL, CONNECTICUT, ASSIGNOR TO THE E. INGRAHAM COMPANY, OF SAME PLACE.

REGULATOR FOR CLOCKS.

SPECIFICATION forming part of Letters Patent No. 332,891, dated December 22, 1885.

Application filed June 30, 1884. Serial No. 136,423. (No model.)

To all whom it may concern:

Be it known that I, GEORGE L. GOODRICH, residing at Bristol, in the county of Hartford and State of Connecticut, have invented certain new and useful Improvements in Regulators for Clocks; and I do declare the following to be a full, clear, and exact description of the same, reference being had to the accompanying drawings, which form a part of this specification.

My invention relates to an improvement in that class of regulators for pendulum-clocks which operate through the spring end of the pendulum-rod, the object being to produce a regulating device of this description which shall be simple and cheap in construction, easy to operate, and adapted to effect a very delicate and close regulation of the clock.

With these ends in view my invention consists in certain details of construction and combinations of parts as will be hereinafter described, and pointed out in the claims.

In the accompanying drawings, Figure 1 is a view in front elevation of the dial of a clock to which my invention has been applied. Fig. 2 is a view in perspective of the front plate of the movement, showing one form which my improved regulating device may assume; and Fig. 3 is a view showing the said plate and the dial in vertical section and the regulating device in side elevation.

As has been stated, my regulating device operates upon the principle of varying the operating length of the pendulum-rod through its spring end.

In carrying out this principle of operation I employ a screw, A, having a milled disk, B, secured to it for operating a device connecting with the spring end C of the pendulum-rod D. As herein shown, the said screw is journaled in and depends from the arm E of a bracket, F, removably secured to the front plate, G, of the clock-movement by a screw, H. The milled disk, which, as described, is secured to the said screw, is arranged to have its edge extend through an elongated slot, I, formed in the dial J, and located above the aperture K, formed therein, to receive the center-shaft of the clock-movement. The screw is connected with the spring end of the pend-

ulum-rod by means of a plate, L, which is provided with a slotted arm, M, from which the rod is suspended, and with a tapped arm, N, which receives the screw. In virtue of this construction and arrangement of parts 55 the plate will be adjusted for raising and lowering the rod, and hence varying its operating length and the rate of its vibration by any movement of the screw to the right or left effected through the milled disk, which is operated by the fingers from the exposed face of the dial. The plate is steadied and guided in its adjustments by means of a pillar, O, secured to it, and having its upper and lower ends respectively journaled in a shoulder, 60 P, and an arm, Q, formed integral with the bracket aforesaid. The spring end of the rod passes through a split stud, R, secured to the front plate of the movement, and forming the virtual point of suspension for the rod. It is 65 to be noted that the entire weight of the pendulum is borne by the plate, which is thus held down in place to receive the slightest impulse imparted to the screw by the movement of the milled disk. It is to be noted also 70 that the greatest impulse that can be imparted to the screw at any one movement of the disk is very slight. This enables the clock to be closely and delicately regulated by an operation not in itself delicate.

It is apparent that the devices for connecting the screw and the spring end of the rod and for mounting the screw are susceptible of modification, looking both to changes in the construction and arrangement of parts and to 85 their adaptation to meet the requirements of different styles of pendulum-clocks. It is also apparent that the arrangement herein shown may be reversed by suspending the rod from a fixed point and passing its spring end 90 through the slotted arm of the adjustable plate. It is further apparent that the disk may be arranged in a vertical rather than a horizontal position in the dial. I would therefore have it understood that I do not limit myself 95 to the exact construction shown and described, but hold myself at liberty to make such changes and alterations as fairly fall within the spirit and scope of my invention.

Having fully described my invention, what 100

I claim as new, and desire to secure by Letters Patent, is—

1. In a regulator for pendulum-clocks, a dial provided with an opening in its face, a screw, a milled disk operated through the opening in the dial for turning the screw, and devices operated by the screw for changing the vibratory length of the pendulum, substantially as set forth.
- 10 2. In a regulator for pendulum-clocks, a screw, a milled disk for turning it, a dial provided with an elongated slot through which the edge of the disk projects, and a device connecting the pendulum and screw, substantially as set forth.
- 15 3. In a regulator for pendulum clocks, a screw, a milled disk for turning it, a bracket having the screw mounted in and depending from it, and a device connecting the pendulum and screw, substantially as set forth.
- 20 4. In a regulator for pendulum-clocks, a

dial provided with an opening in its face, a screw, a milled disk operated through the opening in the dial for turning the screw, and devices operated by the screw for raising and 25 lowering the pendulum, substantially as set forth.

5. In a regulator for pendulum-clocks, a screw, a milled disk for turning it, a bracket in which the screw is mounted, a plate tapped 30 to receive the screw and connecting with the pendulum, and a pillar secured to the said plate and having its ends journaled in the bracket, substantially as set forth.

In testimony whereof I sign this specification in the presence of two subscribing witnesses.

GEORGE L. GOODRICH.
